UNITED STATES PATENT OFFICE.

JULIUS BROWN, OF PEEKSKILL, NEW YORK.

EXPLOSIVE GAS-TURBINE ENGINE.

990,222.

Specification of Letters Patent. Patented Apr. 25, 1911.

Application filed September 12, 1910. Serial No. 581,595.

To all whom it may concern:

Be it known that I, JULIUS BROWN, a citizen of the United States, residing in Peekskill, in the county of Westchester and State of New York, have invented certain new and useful Improvements in Explosive Gas-Turbine Engines, of which the following is a specification.

This invention has for its object to produce an engine of the explosive type, composed of a series of rotary members connected together in two sets which sets are constructed for rotation in opposite directions; and to have the explosive force applied alternately to either set, whereby reversal of the engine is effected.

A further object is to provide an explosion chamber common to all of the rotors, having a valve arranged to control passages leading to the sets, alternately, so that the explosion in the chamber will cause rotation of one set in one direction, or of the other set in the opposite direction.

A further object is to provide a second explosion chamber wherein primary ignition takes place, and thereupon a valve is operated by the engine to open a passage into the main explosion chamber, whereby the exploded charge in the primary ignition chamber will cause combustion of the gases in the main explosion chamber.

A further object is to provide means controlling the valve device leading from the main explosion chamber to the rotors with the valve leading from the ignition chamber to the explosion chamber, which valves are controlled by the rotation of the rotors to be properly timed.

Another object is to provide an adjusting device whereby the operation of the main valve from the explosion chamber to the rotors from the operation of the rotors can be changed to effect reversal of the engine; and such device includes means whereby the operation of the valve leading from the ignition chamber to the explosion chamber will be precisely the same notwithstanding this reversal of the main valve.

In the accompanying drawings representing one embodiment of my invention, Figure 1 shows the invention in side elevation. Fig. 2 is an end view. Fig. 3 is a transverse section on the line 3—3 of Fig. 4. Fig. 4 is a vertical section on the line 4—4 of Fig. 3. Fig. 5 is a section on the line 5—5 of Fig. 4. Fig. 6 is a detailed view enlarged, show-

ing the cam device for operating one valve; and Fig. 7 shows the other valve controlling means.

The invention is shown as comprising a body member B having two sets of cylindrical chambers, in which are mounted rotor members 1, 2, 3, 4, 5 and 6. These rotors are provided with pinions 7, 7, etc., on shafts 8, 8, etc., projecting from each rotor, which pinions all mesh with a gear 9, fast on a short shaft 10; whereby power from the rotors is applied to the shaft, from which the power of the engine is taken. This means that the rotors must all rotate in the same direction, either one way or the other. The specific construction of these rotors forms no part of the present invention, but it is sufficient to state that each comprises blade members 100 having the passages 11 therebetween, the blade members being secured to the shafts 8. The blade members are tubular and at its bore each has a stationary plug 12 having a cross passage 13.

The rotor members 1, 3 and 5 it will be seen, have their blades curved in the same circular direction, and these rotors have inlet passages 14, 15 and 16 leading to a central combustion chamber 17, at the center of the frame member. The other three rotors 2, 4, and 6, it will be seen have their blades extending in the opposite circular direction, to that of said rotors, and these rotors are connected with the explosion chamber 17, by passages 18, 19 and 20, respectively. These rotors are provided with exhaust passages 1^a, 2^a, 3^a, 4^a, 5^a and 6^a on the opposite sides of the rotors from the inlet passages, the pressure fluid passing across the rotors by means of a passage 13 in each of the central plug members 12 on the rotors. These exhaust passages lead around through the frame toward the explosion chamber and then extend lengthwise as indicated in broken lines in Fig. 4, to muffler 23.

In chamber 17 is a tubular valve member 24 having three ports 25, 26 and 27. Upon swinging this valve member these three ports, in one position will register with the three inlets 14, 15 and 16 for the rotors 1, 3 and 5; while in another position of this valve its said three ports will register with the inlet ports 18, 19 and 20, leading to the other three rotors 2, 4 and 6 respectively. And in an intermediate position of the valve member all of these inlet ports will be cut off from the explosion chamber. Hence it

will be seen that this valve can be rocked from said intermediate position to open one set of ports and then rocked back to this position, whereby the three rotors will be supplied with fluid and the engine operated in one direction. While when the valve is rocked from the intermediate position in the opposite direction the other three rotors will be connected for operation. Hence by simply changing the path of oscillation of this tubular valve, the engine can be reversed; either set of rotors being supplied with fluid and the other cut off. Means are provided for oscillating this valve member in either of said two paths automatically from the main shaft 10. In the construction shown, a shaft 28 is driven by a chain 29 from the main shaft 10. A cam shaft 30 supported on the frame carries a cam 31, shown enlarged in Fig. 6. This cam engages an arm 32 adjustably connected with the shaft 33 projecting from the valve member 24. Connected with the cam 31 is a gear 34 that is suitably rotated from the shaft 28. As shown an arm 35 swings on the shaft 28 and carries a gear 36 meshing with the gear 34 in one position of the arm. A sprocket chain 37 passes around a sprocket 38 connected with the gear 36, and also around a sprocket 39 fast on the shaft 38; by which means the gear 36 is rotated that will cause revolution of the cam 31. This will intermittently engage the arm 32 to oscillate the valve member 17. According to the position the arm 32 is adjusted on the shaft carrying the valve, the ports in the valve will connect with either sets of inlet passages for the rotors. In the construction shown, a latch 40 carried on a handle 41 fast on the extremity of the shaft 33 of the valve member, engages with a notch 42 or a notch 43 on the sleeve 44, that carries the arm 32. When the latch engages one of these notches the valve will be swung to cause one set of inlet passages to connect the explosion chamber with three of the rotors turning in one direction; and when the latch is shifted to engage the other notch, the valve member will be shifted whereby the engagement of the cam with the arm will swing the valve to control the admission to the other three rotors; that as understood will cause rotation in the opposite direction. But when this member is shifted, the main shaft 10 will be caused to rotate in the opposite direction. This would result in the cam member 31 rotating in the opposite direction, and being unsymmetrical, the swinging of the valve member would not be the same. Therefore, it is advisable to cause a reversal of the operation of this valve member, whereby it will still operate in the same circular direction. This is effected by swinging the arm 35, carrying the gear 36 that drives the cam gear, whereby gear 36

is shifted out of mesh with the gear 34 and a gear 45 carried by the arm 35 in mesh with the gear 36, is brought into engagement with the gear 34, and the gear 36 shifted out of mesh with the gear 34. This will cause a reversal of the gear 34. But the shaft 28 having been also reversed, this double reversal will cause the gear 34 and the cam to rotate in the same direction as before.

Connected with the main explosion chamber 17 is a second explosion chamber or a primary ignition chamber, of less capacity than the explosion chamber, whose function is to receive compressed gas, cause ignition thereof and immediately thereupon, discharge the same into the explosion chamber directly connected therewith, whereby the explosion in the ignition chamber will cause compression of a charge in the explosion chamber, previously admitted therein that will be exploded by the hot gases from the primary ignition chamber. These two explosion chambers may be connected with different sources of gas supply, such as carburetors.

The frame B is provided with an extension B² cylindrical in shape as shown best in Figs. 4 and 5. The outer end of this chamber is closed by a head 50 having a cylindrical chambered member 51 projecting into the chamber B² with its inner end 52 closed. This chamber 51 also extends out beyond chamber B² and at the outer end is closed by a head 54. In this chamber 51, which constitutes the second explosion chamber, but which may be termed the ignition chamber proper, is a port 55 through which the gases can pass when opened, to the annular chamber 56 surrounding the chamber member 51, and communicating directly with the explosion chamber 17 at the center of the body member. This port 55 is controlled by a tubular valve member 57 having a port 58 that when the valve is swung on its axis will register with the port 55. The valve member 57 is secured to a sleeve 68 loose on shaft 33. These valves are so operated relatively that the port through the valve 57 opens into the main explosion chamber 17, immediately after ignition in the second explosion chamber, to cause ignition in the main explosion chamber, and at the same time the valve 17 is swung to communicate with the three rotors, permitting the charge to act on these members.

The ignition means forms no part of the present invention, but a spark plug 59 is indicated in the main ignition chamber. The primary ignition chamber is shown provided with an inlet pipe 60. A valve 62 controls the admission from an inlet pipe 63 that may connect with a mixer or compressor for providing the charge of explosive gas under pressure which valve may be controlled by the said valve operating

130

mechanism. The gear 34 connected with the cam 31 is shown having a connecting rod 64 pivoted thereon by a crank pin 65, and the rod 64 connects by an arm 66 with 5 the valve 62, whereby the latter is rocked as the cam is rotated. The valve member 57 is rocked through its sleeve 68 by means of a cam 69 fast on the sleeve, that engages lugs 70 and 71 on a cam member 72. The 10 latter is fast on the spindle 30 that carries the cam 31. These lugs cause two operations of the valve member to open the port 58. The inlet pipe 73 for the explosion chamber portion 56 is controlled by a valve 15 74. On this latter is an arm 75 connected to a rod 76 guided in a bracket 77 carried by the machine. A lug 78 on the arm 76 is engaged by a lug 79 on the shaft 30. It will be seen that the three valve members are 20 controlled from this spindle or shaft 30.

The operation of the device is as follows: After an explosion, during which the valve member 24 is held with the three ports open to three of the rotors, and at which time the 25 valve 57 is open from the ignition chamber to the explosion chamber, the valve 62 that has been closed at the time of the ignition, is now opened by the operation of the rod 64 and a compressed charge enters the primary 30 ignition chamber through the inlet 60. This will serve to drive out the exploded gases in the primary ignition chamber into the combustion chamber 17, and from the latter through its three ports to the three 35 rotors, which latter will have a certain amount of exhaustive action tending to drive out these gases. But as soon as the new charge displaces the old charge in the primary chamber the valve 57 is swung by 40 the lug 71 on the cam engaging the crank member 69. This will prevent escape of the compressed charge that will now fill this primary chamber under pressure. Just as soon as the valve 57 closes, the inlet valve 74 for the chamber 56 is opened and a charge 45 admitted that will serve to drive out all of the exploded gas in the chamber 56; which valve is then closed, by the said arm 75 and rod 76. This will cause a fresh charge to be in 50 both the explosion chamber and the primary ignition chamber. The valve 62 thereupon closing, or having closed as soon as a charge is compressed in the primary chamber, the 55 ignition device is operated to cause an explosion in this primary chamber. At the instant that this explosion takes place the valve 57 is again opened by the second lug 70 and the exploded charge will enter the 60 surrounding chamber 56 connecting with the explosion chamber 17, and cause an explosion of the large charge therein. And at this instant the valve 24 that was closed shortly after the valve 74, opened to admit 65 a charge to drive out and replace the exhaust gas in chambers 56 and 17. The exploded

charge in both of the chambers will now find exit through three ports leading to three of the rotors, according to the adjustment of the valve member controlling the direction of rotation, and these three rotors will receive a charge of gas under high pressure that will cause them to rotate. 70

Instead of having the six rotors continuously connected to the driven gear wheel 9, means may be provided for disconnecting either set of three that are inactive or not supplied with fluid pressure. In Fig. 8, three of the shafts 8 have ratchet wheels 81 loose thereon that are engaged by a pawl 83 pivoted on an arm 82 fast on the shaft 8. 80 A spring 84 normally presses the pawls against a ratchet wheel, but they may be withdrawn by pressure on a heel 85, and a pin 86 inserted in the arm to hold the pawls out of engagement with the ratchet wheels. 85 The other three shafts are shown in Fig. 9 as having ratchet wheels 81' carried by arms 82' fast on the shafts. The pawls may be shifted by heels 85' against pressure of spring 84' for insertion of a pin similar to 90 the pin 86. By this means three of the rotors that are not being employed are disconnected and hence are not rotated from the main driving gear.

Having thus described my invention, I 95 claim:

1. In an explosive engine, the combination of a member driven by an explosive charge, an explosion chamber, a second explosion chamber arranged adjacent said explosion chamber and having a port connecting therewith, a valve controlling said port, a gas supply pipe for each of the explosion chambers, means of ignition in the second explosion chamber, means connected with the driven member for operating both said valves whereby a charge exploded in the second ignition chamber is admitted to the first ignition chamber to explode a charge therein and the valve from the first ignition chamber is operated to permit the charge exploded in the main ignition chamber to act on the said driving member. 105

2. In an explosive engine, the combination of a body member having a member driven by an exploded charge, a second member driven by an exploded charge in a direction the opposite to said member, an explosion chamber in the body, ports from the explosion chamber to the said members, a valve member in the explosion chamber arranged to control the ports leading therefrom to the said driven members, said valve member being arranged to alternately connect with the two said sets of driving members whereby to cause the operation of the one or the other, a second explosion chamber arranged adjacent said explosion chamber and having a port connecting with said chamber, a valve member controlling said latter port, a gas 115 120 125 130

supply pipe for each of the explosion chambers, means of ignition in the second explosion chamber, means operatively connected with the driven members for operating both 5 said valve members whereby a charge exploded in the second ignition chamber is admitted to the first ignition chamber to explode a charge therein, and the valve from the first ignition chamber is operated to permit the charge exploded in the main ignition chamber to act on the driven members. 10

3. In an explosive engine, the combination of a body member having a member driven by an exploded charge, a second member 15 driven by an exploded charge in a direction the opposite to said member, an explosion chamber in the body, ports from the explosion chamber to the said members, a valve member in the explosion chamber arranged 20 to control the ports leading therefrom to the said driven members, said valve member being arranged to alternately connect with the two said sets of driving members whereby to cause the operation of the one or the 25 other, a second explosion chamber arranged adjacent said explosion chamber and having a port connecting with said chamber, a valve member controlling said latter port, a gas supply pipe for each of the explosion 30 chambers, means of ignition in the second explosion chamber, means operatively connected with the driven members for operating both said valve members whereby a charge exploded in the second ignition 35 chamber is admitted to the first ignition chamber to explode a charge therein, and the valve from the first ignition chamber is operated to permit the charge exploded in the main ignition chamber to act on the 40 driven members, shifting means for the valve from the main explosion chamber to the rotors whereby the valve will control the ports leading to either set of rotors at will to reverse the engine, said valve operating means 45 for the second combustion chamber being connected with the reversing means whereby the reversal of the main valve will cause it to be operated in the same manner as before reversal. 50

4. In an explosive engine, the combination of a body member having a series of cylindrical chambers, rotors rotatable in said chambers, the body having an explosion chamber and ports connecting the explosion chamber with the said chambers containing the rotors, a valve member in the explosion 55 chamber arranged to control the ports leading therefrom to the said rotors, exhaust ports for the rotors in the body, the body member having a second set of cylindrical chambers, rotors in the latter chambers arranged to rotate in a direction the opposite of the rotation of said rotors, the body having ports leading from the explosion chamber to the 60 said second set of rotors, said valve member being arranged to alternately connect the 65

the ignition chamber valve, and a cam on said spindle engaging said latter arm twice in each revolution of the shaft, means connected with the driven member for rotating the cam shaft. 70

5. In an explosive engine, the combination of a body member having a member driven by an explosive charge, a second member driven by an explosive charge in a direction the opposite to the said member, an explosion chamber in the body, the body having ports connecting the explosion chamber with both said members, a valve member in the explosion chamber arranged to control said ports to alternately connect with the two 80 said driven members whereby to cause the operation of the one or the other, and reverse the engine, a driving member, means connecting said driven members with the driving member whereby the latter is driven in either direction according to which said members are supplied with fluid pressure through the action of the valve member, the said valve in the main explosion chamber being of tubular form and mounted to oscillate, a second explosion chamber having a port communicating with the main explosion chamber, a valve mounted to oscillate in the second ignition chamber, a shaft on which said 85 first valve is secured, an arm connected to said shaft, a spindle mounted to rotate, a cam on the spindle arranged to engage said arm and oscillate the shaft and valve, an arm connected with the ignition chamber valve, and a cam on said spindle engaging 90 said latter arm twice in each revolution of the shaft, means connected with the driven members for rotating the cam spindle, said arm on the valve shaft being adjustable 95 whereby the cam will shift the valve to control the ports to either driven members according to the position shifted to reverse the engine, and means connected with said shiftable arm to cause a reversal of the movement 100 imparted to the cam shaft from the driven members, whereby the cam shaft always rotates in the same direction notwithstanding reversal of the driven members. 105

6. In an explosive engine, the combination of a body member having a series of cylindrical chambers, rotors rotatable in said chambers, the body having an explosion chamber and ports connecting the explosion chamber with the said chambers containing the rotors, a valve member in the explosion 110 chamber arranged to control the ports leading therefrom to the said rotors, exhaust ports for the rotors in the body, the body member having a second set of cylindrical chambers, rotors in the latter chambers arranged to rotate in a direction the opposite of the rotation of said rotors, the body having ports leading from the explosion chamber to the 115 said second set of rotors, said valve member being arranged to alternately connect the 120

125

130

two said sets of rotors with the explosion chamber whereby to cause the rotation of the one or the other set, a driving member, means connecting all of said rotors with the 5 driving member whereby the latter is driven in either direction according to which set of rotors are supplied with fluid through the action of the valve member, a second explosion chamber arranged adjacent said explosion chamber and having a port connecting with such chamber, a valve member controlling said latter port, a gas supply pipe for each of the explosion chambers, means of ignition in the second explosion chamber, 10 means connected with the rotors for operating both said valve members whereby a charge exploded in the second ignition chamber is admitted to the first ignition chamber to explode a charge therein, and 15 the valve from the first ignition chamber is operated to permit the charge exploded in the main ignition chamber to act on the rotors.

7. In an explosive engine, the combination 20 of a body member having a series of cylindrical chambers, rotors rotatable in said chambers; an explosion chamber in the body, the body having ports connecting the explosion chamber with the said chambers containing the rotors, a valve in the explosion chamber arranged to control the ports leading therefrom to the said rotors, exhaust ports for the rotors in the body, the body member having a second set of cylindrical chambers, 25 rotors in the latter chambers arranged to rotate in a direction the opposite of the rotation of said rotors, the body having ports leading from the explosion chamber to the said second set of rotors, said valve being arranged to alternately connect the explosion chamber with the two said sets of 30 rotors whereby to cause the rotation of the one or the other set, a driving member, means connecting all of said rotors with the 35 driving member whereby the latter is driven in either direction according to which set of rotors are supplied through the action of the valve member, a second explosion chamber arranged adjacent said explosion chamber 40 and having a port connecting with such chamber, a valve controlling said port, a gas supply pipe for each of the explosion chambers, means of ignition in the second explosion chamber, means connected with the rotors 45 for operating said valves whereby a charge exploded in the second ignition chamber is admitted to the first ignition chamber to explode a charge therein, and the valve from the first ignition chamber is 50 operated to permit the charge exploded in the main ignition chamber to act on the rotors, shifting means for the valve from the main explosion chamber to the rotors whereby the valve will control the ports leading to 55 either set of rotors at will to reverse the en-

gine, said valve for the second ignition chamber being connected with the reversing means whereby the reversal of the main valve will cause it to be operated in the same manner as before reversal.

70

8. In an explosive engine, the combination of a member driven by an explosive charge, an explosion chamber, a second explosion chamber having a port connecting with said explosion chamber, a valve controlling said port, a gas supply pipe for each of the explosion chambers, a valve in each of said latter pipes, means of ignition in the second explosion chamber, operative means connected with the driven member for each of said four valves and being constructed and timed whereby immediately upon the explosion in the ignition chamber its valve is opened permitting the exploded gas to enter the first said explosion chamber and explode a charge therein, and at the same time the valve in the latter explosion chamber is opened permitting the exploded gas therein to act on the driven member, thereupon the inlet valve for the 90 second explosion chamber is opened to permit admission of a charge to drive out the exhaust gas therein, and thereupon the outlet valve for the second explosion chamber is closed and also the inlet valve therefor, thereupon the inlet valve for the first ignition chamber is opened permitting admission of a charge to drive out the exhaust gas from the first explosion chamber and thereupon the outlet valve for the first explosion chamber leading to the driven member is closed and also the said inlet valve for this chamber.

95

100

9. In an explosive engine, the combination of a member driven by an explosive charge, an explosion chamber, a second explosion chamber having a port connecting with said explosion chamber, a valve controlling said port, a gas supply pipe for each of the explosion chambers, a valve in each of said latter pipes, means of ignition in the second explosion chamber, operative means connected with the driven member for each of said four valves and being constructed and timed whereby immediately upon the explosion in the ignition chamber its valve is opened permitting the exploded gas to enter the first said explosion chamber and explode a charge therein, and at the same time the valve in the latter explosion chamber is opened permitting the exploded gas therein to act on the driven member, thereupon the inlet valve for the second explosion chamber is opened to permit admission of a charge to drive out the exhaust gas therein, and thereupon the outlet valve for the second explosion chamber is closed and also the inlet valve therefor, thereupon the inlet valve for the first ignition chamber is opened permitting ad-

105

110

115

120

125

130

mission of a charge to drive out the exhaust gas from the first explosion chamber and thereupon the outlet valve for the first explosion chamber leading to the driven member is closed and also the said inlet valve for this chamber, and a second member driven by an explosive charge having a port connecting with said first explosion chamber that is controlled by said valve in the latter, the operating means for said latter valve being adjustable to cause it to admit the charge from the first explosion chamber to either of said driven members without varying its timed relation to said other three valves.

10. In an explosive engine, the combination of a body member having a series of cylindrical chambers, rotors rotatable in said chambers, the body having an explosion chamber and ports connecting the explosion chamber with the said chambers containing the rotors, a valve member in the explosion chamber arranged to control said ports, exhaust ports for the rotors in the body, the body member having a second set of cylindrical chambers, rotors in the latter chambers arranged to rotate in a direction the opposite of the rotation of said rotors, exhaust ports for the latter rotors, the body having ports leading from the combustion chamber to the said second set of rotors, said valve member being arranged to alternately connect the two said sets of rotors with the explosion chamber, whereby to cause the rotation of the one or the other set, a driving member, and means connecting

all of said rotors with the driving member whereby the latter is driven in either direction according to which set of rotors are supplied with fluid through the action of the valve member.

11. In an explosive engine, the combination of a body member having a series of cylindrical chambers, rotors rotatable in said chambers, the body having an explosion chamber and ports connecting the explosion chamber with the said chambers containing the rotors, a valve member in the explosion chamber arranged to control said ports, exhaust ports for the rotors in the body, the body member having a second set of cylindrical chambers, rotors in the latter chambers arranged to rotate in a direction the opposite of the rotation of said rotors, exhaust ports for the latter rotors, the body having ports leading from the combustion chamber to the said second set of rotors, said valve member being arranged to alternately connect the two said sets of rotors with the explosion chamber, whereby to cause the rotation of the one or the other set, a driving member, and means connecting all of said rotors with the driving member whereby the latter is driven in either direction according to which set of rotors are supplied with fluid through the action of the valve member.
